Specification for Design.

Patented Apr. 17, 1917.

Application filed March 20, 1917. Serial No. 156,211. Term of patent 3½ years.

To all whom it may concern:

Be it known that I, EUGENE IRVING HANSON, a citizen of the United States of America, and a resident of New Rochelle, county of Westchester, and State of New York, have invented a new, original, and ornamental Design for a Textile Fabric, of which the following is a specification, reference being had to the accompanying drawing, showing my design.

The drawing shows a face view of a portion of fabric bearing my design.

In the drawing I have shown by way of example the design in a red color upon a white background. I want it distinctly understood, however, that said colors may be varied without departing from my invention.

The design is intended to be repeated on the fabric.

I claim:

The design for a textile fabric substantially as shown and described.

EUGENE IRVING HANSON.
